[57] **CLAIM**

The ornamental design for a shovel, as shown and described.

DESCRIPTION

FIG. 1 is an isometric view of a shovel in accordance with the present invention;

FIG. 2 is a top plan view of the shovel of FIG. 1;

FIG. 3 is a front elevational view of the shovel of FIG. 1;

FIG. 4 is a side elevational view of the shovel of FIG. 1;

FIG. 5 is an opposite side elevational view of the shovel of FIG. 1;

FIG. 6 is a rear elevational view of the shovel of FIG. 1; and,

FIG. 7 is a bottom plan view of the shovel of FIG. 1.

The broken line showing of a shovel shaft is for illustrative purposes only and forms no part of the claimed design.
